UNITED STATES PATENT OFFICE.

MARTEN BALCKER, OF CHICAGO, ILLINOIS.

HYDRAULIC AIR COMPRESSOR.

Application filed June 15, 1923. Serial No. 645,486.

To all whom it may concern:

Be it known that I, MARTEN BALCKER, a citizen of the United States, residing at Chicago, in the county of Cook and State of Illinois, have invented certain new and useful Improvements in Hydraulic Air Compressors, of which the following is a specification.

This invention relates to improvements in hydraulic air compressor of the type in which the air is compressed by columns of liquid through the medium of a rotor or impeller which operates on the liquid to impart motion thereto and one of the objects of the invention is to provide an improved apparatus of this character embodying means for automatically controlling or directing the course of flow of the liquid.

A further object is to provide an improved apparatus of this character embodying means influenced by the liquid pressure for changing the direction of flow of the liquid.

A further object is to provide an improved apparatus of this character in which the rotor or impeller will be balanced in its chamber.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention and in which

Figure 1 is a vertical, longitudinal sectional view of an apparatus constructed in accordance with the principles of this invention and as taken on line 1—1, Figure 2.

Figure 2 is a vertical sectional view taken on line 2—2, Figure 1.

Figure 3 is a detail, vertical sectional view taken on line 3—3, Figure 2.

Figure 4 is a detail sectional view taken on line 4—4, Figure 2.

Figure 5 is a horizontal sectional view taken on line 5—5, Figure 1.

Figure 6 is a top plan view of Figure 1.

Figure 7 is a horizontal sectional view taken on line 7—7, Figure 1.

Figure 8 is a horizontal sectional view taken on line 8—8, Figure 3.

Referring more particularly to the drawings the numerals 10 and 11 designate cylinders of any desired size and diameter.

These cylinders are preferably arranged uprightly and are provided respectively in their bottoms with openings 12—13, through which openings liquid will flow from and into a chamber 14 arranged beneath the cylinders.

The openings 12—13 are respectively controlled by means of cut off devices 15—16 in the form of valves and are respectively provided with openings 17—18 therein adapted to be moved into and out of register with the respective openings 12 and 13 when the valve or cut off members are rotated. The cut off or valve member 15 is provided with a stem 19 rotatably mounted in a suitable bearing 20 and the cut off member 16 is provided with a similar stem 21 rotatably mounted in a suitable bearing 22.

The cut off members 15 are connected for oscillation in unison so that when one of them is moved to uncover the respective inlet openings in the bottom of the cylinder the cut off for the openings in the bottom of the other cylinder will be closed, and vice versa.

Any suitable means may be provided for accomplishing this result but there is preferably provided a crank arm 23 which is connected with the stem 19 of the cut off 15 and a crank arm 24 connected with the stem of the cut off 16 (see particularly Figures 3 and 5). A link 25 is pivotally connected with each of the crank arms 23 and 24 and through the medium of this link when one of the cut offs is rotated to open the ports which it controls the other cut off will be rotated to close its respective ports.

The cut off 15 is provided with an upwardly extending and slightly curved deflector or baffle 26, and the cut off 16 is provided with a similar deflector or baffle 27, for purposes which will be later described.

The cylinder 10 is provided with an air inlet opening 28 (see particularly Figure 1) controlled by a spring influenced valve 29 and is also provided with a discharge outlet opening controlled by a spring controlled valve 30. The valves 29 and 30 open in opposition to each other and the valve 30 controls the outlet of the cylinder which outlet has communication with a chamber 31 from which chamber a discharge pipe 32 leads.

The cylinder 11 is provided with an air inlet opening 33 controlled by a spring influenced valve 34 and is also provided with

a discharge outlet opening controlled by a spring influenced valve 35 the outlet opening having communication with the chamber 31. The valves 34 and 35 also work in opposite position to each other.

Floats 36-37 are respectively arranged in the chambers 10 and 11 and the chambers are respectively provided with supports or stops 38-39 arranged adjacent the bottom thereof, and which supports or stops are adapted to be engaged by the floats 36-37 for supporting the floats and for limiting their movement in one direction in the cylinders.

Arranged beneath the chamber 14 is a rotor or impeller chamber 40 (see particularly Figure 7) and disposed within the chamber 40 is a rotor or impeller 41 which may be of any desired configuration but is preferably of a cup shape formation having an upwardly extending peripheral wall 42, through which latter extend a plurality of outlet openings 43. The bottom of the rotor is also provided with openings 44 and the rotor or impeller is supported by means of a shaft 45 journaled in a suitable bearing 46 and resting in a step or bearing 47. Connected with the shaft 45 is a pulley 48, by means of which the shaft is rotated.

If desired and in order to prevent the impeller from sucking or drawing in outside air a suitable packing 49 may be arranged in a chamber or recess 50 formed in the bearing 46. The packing is preferably of a U shape formation opening upwardly so that if there should be any tendency of the outside air to enter the chamber 40 the packing will expand and will form a fluid tight joint.

Leading from the chamber 40 and preferably arranged tangential to the impeller are outlet passages 51-52 which lead upwardly as at 53-54 (see particularly Figures 1, 2 and 3). By arranging the passages 51-52 tangential to the impeller it will be manifest that the centrifugal force or speed imparted to the liquid by the impeller will not be interfered with and the flow of the liquid from the impeller chamber and through the passages 51-52 will not be impeded.

The impeller 41 is supported by the shaft 45 within the chamber 40 in such a position that it will be spaced from all of the walls of the chamber thereby permitting the liquid to completely surround or immerse the impeller and insuring a uniform pressure upon all points of the impeller from all faces thereof, thereby balancing the impeller.

A communicating passage 55 leads from the chamber 14 to the impeller chamber 40 to supply the liquid to the impeller. Disposed above the cut offs 15 and 16 is a valve chamber 56, within which is arranged a hollow rotary valve 57. The valve chamber is provided with removable closures 58-59

and removable elements 60-61, between which the valve is held. The member 60 may be secured in position by means of a suitable securing device 62, and is hollow as at 63 to permit liquid to flow therethrough to the valve. The valve is provided with a stem 64, which is journaled in the member 60, the latter being preferably held in position between the end of the valve and the closure 59, so that the valve may be rotated within the casing. The valve is provided with two outlet ports 65-66, adapted to be respectively brought into register with ports or passages 67-68, which latter are respectively provided with discharge outlets 69-70, adjacent the lower ends of the cylinders 10 and 11. These discharge outlets 69-70 are respectively so located with respect to the deflectors or baffles 26-27 on the cut offs 15 and 16 that when liquid is allowed to flow through either of the passages 67-68 it will be directed against one or the other of the deflectors or baffles 26-27 according to the position of the valve 57 and thereby serve as a means for rotating the cut offs so as to open or close the respective inlet openings 12-13 at the bottoms of the respective cylinders 10 and 11.

The discharge outlets 53-54 leading from the impeller chamber 40 discharge into the valve casing 56 (see particularly Figure 2) in rear of the valve 57 so that liquid which is being discharged by the impeller 41 from the impeller chamber 40 through either of the passages 53-54 will be directed into and through the valve 57 and therefrom through the openings 65-66, through whichever of the passages 67-68 is open by the position of the valve 57. The ports 65-66 in the valve 57 are so arranged with respect to each other that when the valve 57 is positioned to open one of the passages 67-68, the other passage will be closed by the valve.

It will therefore be manifest that the operation of the cut offs 15-16 will be controlled and influenced by the liquid being discharged through the passages 67 and 68. In order therefore to change the direction of flow of the liquid and to control the operation of the cut offs 15 and 16, it is only necessary to control the valve 57. Means are provided whereby the valve 57 may be automatically actuated by the liquid through the medium of the pressure created thereupon and to that end there is provided a passageway 71 leading from the chamber 10 adjacent the bottom thereof, which terminates at a point adjacent the top of the cylinder and communicates with a valve chamber 72 and leading from this valve chamber 72 is a passage 73, which discharges into the valve casing 56 in advance of the valve 57. A spring controlled valve 74 is arranged in the valve chamber 72 for closing the passages 71 and 73. The valve

chamber 72 has communication with the chamber 31 through a passage 75.

Leading from the cylinder 11 adjacent the bottom thereof is a passage 76, similar to the passage 71 and which passage 76 has communication with a valve chamber 77, adjacent the upper end of the cylinder 11. A passage 78 leads from the valve chamber 77 and discharges into the valve casing 56 in advance of the valve 57 (see particularly Figures 2 and 4). The member 60, which is disposed in the valve casing 56 intermediate the valve 57 and the removable closure 59 is cut away as at 79 (see particularly Figures 2 and 4) and connected with the stem 64 of the valve 57 is a wing 80. This wing 80 is adapted to operate in the cut away portion 79 of the member 60 and is so arranged that it may be alternately moved into a position that it will close the outlet openings of the passages 73-78.

Within the valve chamber 77 is a spring controlled valve 81 similar to the valve 74 and the valve chamber 77 has communication with the chamber 31 through a suitable passage 82.

Under normal conditions the spring controlled valves 74 and 81 will be seated so as to respectively close the passages 71-73 and 76-78 but when pressure is exerted upon the valves 74-81 sufficient to unseat the valves the passages will be opened so as to permit liquid from the respective cylinders 10 and 11 to flow through the respective passages 71-73 and 76-78 to be discharged against the wing 80 to shift the latter and thereby rotate the valve 57, it being understood that the pressure of the liquid will be exerted upon one side of the wing 80.

To start the apparatus a sufficient quantity of liquid is placed therein preferably through a fill opening closed by means of a plug or closure 83, until the liquid has reached a predetermined level. Inasmuch as the cut offs 15 and 16 operate in opposition to each other, it will be manifest, and as has been before stated, they will be in positions that either one or the other of the openings 12-13 in the bottoms of the cylinders 10 and 11 will be opened and the other will be closed. The valve 57 will be positioned so as to cause either of the ports or passages 65-66 thereof to be respectively in register with that one of the passages 67-68 which discharges the liquid into that one of the cylinders 10 or 11 in which the respective inlets 12-13 is closed by the cut off 15 or 16.

With the parts in this position, the apparatus will be ready to start and the floats 36-37 will be resting upon the surface of the liquid.

The impeller is then started and as it rotates the liquid in the impeller chamber 40 will be discharged through the outlet passages 51-52 into the passages 53-54. One

of the passages 67-68, however, will be closed by the position of the valve 57, as for instance as shown in Figure 3. This will shut off the flow of the liquid through the passage 67 and the liquid will then circulate through the passages 53-54 into the valve casing 56 into the valve 57, through the port 66 and into the cylinder 11, shifting the cut off 16 and closing the inlet passage 13 to the cylinder 11. Any liquid which was contained in the cylinder 10 will flow out of the opening 12 in the bottom thereof into the chamber 14, through the passage 55 into the impeller chamber 40. The float 36 will be lowered with the lowering of the liquid level until it engages and rests upon the stops and supports 38. The liquid will be continued to be forced into the cylinder 11 and as the liquid accumulates therein, the float 37 will rise. As the float rises the air which is contained in the cylinder 11 above the float will be compressed and after compression will unseat the valve 35 so that the air will be discharged into the chamber 31 and out of the outlet 32. As the liquid rises in the cylinder 11 it will also rise in the passage 76 and the valve 81 will remain seated until the pressure exerted upon the liquid will overcome the opposing pressure exerted upon the valve to unseat the latter. At just about this point in the operation the float 37 will assume the position shown in Figure 1, that is at the extreme top of the cylinder and will serve as a means for assisting in closing the air outlet passage and the air inlet passage to that cylinder. As the pressure of the liquid increases in the cylinder 11, the same pressure will be manifested upon the column of liquid in the passage 76 and as the valve 81 is unseated the passage 78 will be opened so that the liquid will then flow from the passage 78 (see Figures 1 and 4) to be discharged against the wing 80 on the valve stem 64. This pressure of the liquid on the wing 80 will shift the latter from the position shown in Figure 4 so as to open the passage 67 and cause the wing 80 to assume a position to close the passage 73. This operation of the wing 80 will rotate the valve 57 and will shift the same from the position shown in Figure 3 to move the port 66 out of register with the passage 68 and cause the port 65 to move into register with the passage 67. The direction of flow of the liquid will then be changed and the liquid will be diverted through the passage 67 and out of the outlet 69 at the bottom of the cylinder 10 against the baffle or deflector 26. The impact or pressure of the liquid upon this baffle 26 will rotate the cut off 15 and in so rotating the latter, the cut off 16 will be shifted through the medium of the link 25 so that the passage 12 at the bottom of the cylinder 10 will be closed and the passage 13 at the bottom of the cylinder 11

will be opened. The liquid will then, under the influence of the impeller 41, be drawn through the opening 13 into the chamber 14 and through the passage 55 into the impeller 6 chamber to be discharged therefrom through the passage 51 into the passage 53, thence, to the valve casing 56 through the valve 57, out of the port 65, through the passage 67 and into the cylinder 10. As the liquid accumulates in the cylinder 10 the float 36 will rise and compression of the air will be created in the cylinder 10 in the same manner as described in connection with the cylinder 11. When the pressure upon the liquid column in the passage 71 is sufficient to unseat the valve 74 the liquid will flow through the passage 73 to be discharged against the wing 80 connected with the valve stem 64 to shift the wing 80 back to the position shown in Figure 4, when one cycle of operation will be completed.

It will therefore be manifest that with this operation the liquid is caused to rise first in one cylinder and then in the other, and as it rises in one cylinder it falls or recedes in the other.

As the liquid falls or recedes in either one or the other of the cylinders 10 and 11 air will be sucked thereinto through the respective air inlet passages 28-33, as will be understood, and as the air is compressed and discharged from the cylinders it will enter the chamber 31.

If desired and as a means for disposing of any excess liquid which may be discharged from the passages 73-78 into the space 79 of the valve casing and on either side of the wing 80, there may be provided a passage 84 (see particularly Figures 2 and 4) having inlets 85-86 communicating with the space 79 on the opposite sides of the wings 80, and leading from this passage 84 is a passage 87 which has communication with the chamber 14 to convey the liquid back to the chamber 14.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

55 1. A compressor embodying a plurality of compressing chambers each having a fluid inlet and an outlet for compressed fluid, means for delivering a liquid into the chambers for compressing the fluid, the said means including an impeller for creating a pressure upon the liquid, and means operating automatically to cause the liquid to compress the fluid in the said chambers alternately.

60 2. A compressor embodying a plurality of compressing chambers each having a fluid

inlet and an outlet for compressed fluid, means for delivering a liquid into the chambers for compressing the fluid, the said means including an impeller for creating a pressure upon the liquid, and means operating automatically to cause the liquid to compress the fluid in the said chambers alternately, the last recited means embodying mechanism for changing the course of flow of the liquid from one of the chambers to another chamber while the direction of operation of the said impeller remains constant.

3. A compressor embodying a plurality of compressing chambers each having a fluid inlet and an outlet for compressed fluid, means for delivering a liquid into the chambers for compressing the fluid, the said means including an impeller for creating a pressure upon the liquid, and means influenced by the liquid pressure for causing the fluid to be compressed alternately in the said chambers.

4. A compressor embodying two compressing chambers each having a fluid inlet and an outlet for compressed fluid, an impeller for forcing liquid into the chambers for compressing the fluid therein, valve mechanism for changing the course of flow of the liquid from one chamber to the other, means operatively connected with the valve mechanism and directly operated upon by the liquid for shifting the valve, and fluid controlled means for controlling the action of the liquid upon the first recited means.

5. A compressor embodying two compressing chambers each having a fluid inlet and an outlet for compressed fluid, an impeller for forcing liquid into the chambers for compressing the fluid therein, valve mechanism for changing the course of flow of the liquid from one chamber to the other, and means operating automatically to actuate the said valve.

6. A compressor embodying two compressing chambers each having a fluid inlet and an outlet for compressed fluid, an impeller for forcing the liquid into the chambers for compressing the fluid therein, and means whereby the liquid pressure will operate to cause the liquid to be withdrawn from one of the said chambers and supplied to the other of the chambers.

7. A compressor embodying two compressing chambers each having a fluid inlet and an outlet for compressed fluid, an impeller for forcing the liquid into the chambers for compressing the fluid therein, and means whereby the liquid pressure will operate to cause the liquid to be withdrawn from one of the said chambers and supplied to the other of the chambers, the said means including cut off devices for cutting off the supply of liquid to the cylinders and working in opposition to each other.

8. A compressor embodying two compressing chambers each having a fluid inlet and an outlet for compressed fluid, an impeller for forcing the liquid into the chambers for compressing the fluid therein, means whereby the liquid pressure will operate to cause the liquid to be withdrawn from one of the said chambers and supplied to the other of the chambers, the said means including cut off devices for cutting off the supply of liquid to the cylinders and working in opposition to each other, and means whereby the said cut off devices will be actuated by the action of the liquid thereupon.
- 15 9. A compressor embodying two compressing chambers each having at one end a valve controlled fluid inlet and an outlet for compressed fluid, a liquid inlet and outlet passage at the other end of each of the chambers, a liquid chamber with which the said liquid inlet and outlet passages communicate whereby the liquid may flow out of and into the liquid chamber through said passage, an impeller operating upon the liquid, a cut off for each of the said liquid passages, means causing the cut offs to operate in opposition to each other, and means for changing the course of flow of the liquid to actuate the cut offs.
- 39 10. A compressor embodying two compressing chambers each having at one end a valve controlled fluid inlet and an outlet for compressed fluid, a liquid inlet and outlet passage at the other end of each of the chambers, a liquid chamber with which the said liquid inlet and outlet passages communicate whereby the liquid may flow out of and into the liquid chamber through said passage, an impeller operating upon the liquid, a cut off for each of the said liquid passages, means causing the cut offs to operate in opposition to each other, and means influenced by the liquid pressure for changing the course of flow of the liquid to actuate the cut offs.
- 50 11. A compressor embodying two compressing chambers each having at one end a valve controlled fluid inlet and an outlet for compressed fluid, a liquid inlet and outlet passage at the other end of each of the chambers, a liquid chamber with which the said liquid inlet and outlet passages communicate whereby the liquid may flow out of and into the liquid chamber through said passage, an impeller operating upon the liquid, a cut off for each of the said liquid passages, means causing the cut offs to operate in opposition to each other, a valve device for changing the course of flow of the liquid to actuate the cut offs, and fluid pressure means for actuating the said valve device.
- 65 12. A compressor embodying two compression chambers each having a fluid inlet and an outlet for compressed fluid, an impeller chamber having communication with each of the compression chambers, an impeller in the impeller chamber, means for causing the compression chambers to be alternately brought into communication with the impeller chamber and alternately cut off therefrom, and means responsive in its operation to the liquid pressure for changing the course of flow of the liquid to cause the latter to flow from one of the compression chambers into the other.
13. A compressor embodying two compression chambers each having a fluid inlet and an outlet for compressed fluid, an impeller chamber having communication with each of the compression chambers, an impeller in the impeller chamber, means for causing the compression chambers to be alternately brought into communication with the impeller chamber and alternately cut off therefrom, and means responsive in its operation to the liquid pressure for changing the course of flow of the liquid to cause the latter to flow from one of the compression chambers into the other and through the impeller while the direction of operation of the impeller remains constant.
14. A compressor embodying two compression chambers each having a fluid inlet and an outlet for compressed fluid, an impeller chamber having communication with each of the compression chambers, an impeller in the impeller chamber, cut off devices individual to the compression chambers for controlling the communications with the impeller chamber, means for changing the direction of flow of the liquid for causing the liquid to flow from one of the compression chambers to the other, means whereby the change in the direction of flow of the liquid will actuate the said cut offs, and liquid pressure actuated means for controlling the actuation of the first recited means.
15. A compressor embodying two compression chambers each having a fluid inlet and an outlet for compressed fluid, an impeller chamber having communication with each of the compression chambers, an impeller in the impeller chamber, cut off devices individual to the compression chambers for controlling the communications with the impeller chamber, means for changing the direction of flow of the liquid for causing the liquid to flow from one of the compression chambers to the other, means whereby the change in the direction of flow of the liquid will actuate the said cut offs, the last recited means embodying baffles connected with the said cut off adapted to be impacted by the liquid, and liquid pressure actuated means for controlling the actuation of the first recited means.
16. A compressor embodying a compression chamber having a fluid inlet and an

- outlet for compressed fluid, an impeller chamber having communication with the compression chamber, a cut off for controlling the communication between the compression and impeller chambers, means for changing the direction of flow imparted to the liquid by the impeller, and means whereby the change in the direction of flow of the liquid will actuate the said cut off.
17. A compressor embodying a compression chamber having a fluid inlet and an outlet for compressed fluid, an impeller chamber having communication with the compression chamber, a cut off for controlling the communication between the compression and impeller chambers, means for changing the direction of flow imparted to the liquid by the impeller, while the direction of operation of the impeller remains constant, and means whereby the change in the direction of flow of the liquid will actuate the said cut off.
18. A compressor embodying a compression chamber having a fluid inlet and an outlet for compressed fluid, an impeller chamber having communication with the compression chamber, a cut off for controlling the communication between the compression and impeller chambers, means for changing the direction of flow imparted to the liquid by the impeller, liquid pressure controlled means for controlling the actuation of the last recited means, and means whereby the change in the direction of flow of the liquid will actuate the said cut off.
19. A compressor embodying a compression chamber having a fluid inlet and an outlet for compressed fluid, an impeller chamber having communication with the compression chamber, an impeller in the impeller chamber, a cut off for controlling the communication between the compression and impeller chambers, means operating automatically at a predetermined time in the cycle of operation of the apparatus for changing the direction of flow imparted to the liquid by the said impeller, and means whereby the change in direction of flow of the liquid will actuate the said cut off.
20. A compressor embodying a compression chamber having a fluid inlet and an outlet for compressed fluid, an impeller chamber having communication with the compression chamber, an impeller in the impeller chamber, a cut off for controlling the communication between the compression and impeller chambers, means operating automatically at a predetermined time in the cycle of operation of the apparatus for changing the direction of flow imparted to the liquid by the said impeller, and means whereby the change in direction of flow of the liquid will actuate the said cut off, the last recited means embodying means operationally connected with the said cut off and adapted to be impacted by the liquid.
21. A compressor embodying a compression chamber having a fluid inlet and an outlet for compressed fluid, an impeller chamber having communication with the compression chamber, an impeller in the impeller chamber, a cut off for controlling the communication between the compression and impeller chambers, means operating automatically at a predetermined time in the cycle of operation of the apparatus for changing the direction of flow imparted to the liquid by the said impeller and while the direction of operation of the said impeller remains constant, and means whereby the change in direction of flow of the liquid will actuate the said cut off.
22. A compressor embodying a compression chamber having a fluid inlet and an outlet for compressed fluid, an impeller chamber having communication with the compression chamber, a pressure balanced impeller in the impeller chamber, a cut off for controlling the communication between the said chambers, means operating automatically at a predetermined time in the cycle of operation of the apparatus for changing the direction of flow imparted to the liquid by the said impeller, and means whereby the change in the direction of flow of the liquid will actuate the said cut off.
23. A compressor embodying two compression chambers, each having a fluid inlet and an outlet for compressed fluid, each of said chambers having a liquid inlet and outlet passage, a cut off for each of the last recited passages, means for imparting motion to the liquid to cause the same to flow into one of the chambers to compress the fluid therein and out of the other chamber to cause fluid to flow thereinto, and means operating automatically to change the direction of flow of the liquid.
24. A compressor embodying two compression chambers, each having a fluid inlet and an outlet for compressed fluid, each of said chambers having a liquid inlet and outlet passage, a cut off for each of the last recited passages, means for imparting motion to the liquid to cause the same to flow into one of the chambers to compress the fluid therein and out of the other chamber to cause fluid to flow thereinto, means whereby the change in the direction of flow of the liquid will automatically actuate the said cut offs, and means operating automatically to change the direction of flow of the liquid.
25. A compressor embodying two compression chambers, each having a fluid inlet and an outlet for compressed fluid, each of said chambers having a liquid inlet and outlet passage, a cut off for each of the last recited passages, means for imparting motion to the liquid to cause the same to flow into one of the chambers to compress the

- fluid therein and out of the other chamber to cause fluid to flow therewith, means operating automatically to change the direction of flow of the liquid, and means connected with the cut offs and adapted to be impacted by the liquid for actuating the cut offs.
26. A compressor embodying two compression chambers, each having a fluid inlet and an outlet for compressed fluid, each of said chambers having a liquid inlet and outlet passage, a cut off for each of the last recited passages, means for imparting motion to the liquid to cause the same to flow into one of the chambers to compress the fluid therein and out of the other chamber to cause fluid to flow therewith, valve mechanism for changing the direction of flow of the liquid, liquid pressure actuated means for automatically actuating the valve mechanism, and means whereby the change in the direction of flow of the liquid will actuate the said cut offs.
27. A compressor embodying two compression chambers, each having a fluid inlet and an outlet for compressed fluid, each of said chambers having a liquid inlet and outlet passage, a cut off for each of the last recited passages, means for imparting motion to the liquid to cause the same to flow into one of the chambers to compress the fluid therein and out of the other chamber to cause fluid to flow therewith, valve mechanism for changing the direction of flow of the liquid, liquid pressure actuated means for automatically actuating the valve mechanism, and means whereby the change in the direction of flow of the liquid will actuate the said cut offs, the last recited means embodying formations connected with the cut offs and adapted to be impacted by the liquid.
28. A compressor embodying two compression chambers, each having a fluid supply inlet and an outlet for compressed fluid, a supply of liquid, means for causing the liquid to flow into one of the chambers to compress fluid therein and out of the other chamber to cause fluid to flow into the latter, a liquid by-pass passage for each of the chambers, a valve for controlling the by-pass passage, said valve operating to change the direction of flow of the liquid, pressure controlled means for actuating the said valve, there being a liquid passage leading from each of the said chambers for conveying pressure to the last recited means, and pressure controlled means for controlling the last recited passages.
29. A compressor embodying two compression chambers, each having a fluid supply inlet and an outlet for compressed fluid, a supply of liquid, means for causing the liquid to flow into one of the chambers to compress fluid therein and out of the other
- chamber to cause fluid to flow into the latter, a liquid by-pass passage for each of the chambers, a valve for controlling the by-pass passage, said valve operating to change the direction of flow of the liquid, pressure controlled means for actuating the said valve, there being a liquid passage leading from each of the said chambers for conveying pressure to the last recited means, pressure controlled means for controlling the last recited passages, and means operating automatically to close to the exit of the liquid, that chamber into which the liquid is being delivered.
30. A compressor embodying two compression chambers, each having a fluid supply inlet and an outlet for compressed fluid, a supply of liquid, means for causing the liquid to flow into one of the chambers to compress fluid therein and out of the other chamber to cause fluid to flow into the latter, a liquid by-pass passage for each of the chambers, a valve for controlling the by-pass passage, said valve operating to change the direction of flow of the liquid, pressure controlled means for actuating the said valve, there being a liquid passage leading from each of the said chambers for conveying pressure to the last recited means, pressure controlled means for controlling the last recited passages, and means operating automatically to close the exit of the liquid, that chamber into which the liquid is being delivered, the last recited means embodying mechanisms responsive, in its operation to the flow of the liquid.
31. A compressor embodying two compression chambers, each having a fluid supply inlet and an outlet for compressed fluid, a supply of liquid, means for causing the liquid to flow into one of the chambers to compress fluid therein and out of the other chamber to cause fluid to flow into the latter, a liquid by-pass passage for each of the chambers, a valve for controlling the by-pass passage, said valve operating to change the direction of flow of the liquid, pressure controlled means for actuating the said valve, there being a liquid passage leading from each of the said chambers for conveying pressure to the last recited means, pressure controlled means for controlling the last recited passages, and means operating automatically to close to the exit of the liquid, that chamber into which the liquid is being delivered, the last recited means embodying cut offs and formations connected therewith adapted to be impacted by the liquid.
32. A compressor embodying two compression chambers each having a fluid inlet and an outlet for compressed fluid, an impeller chamber having communication with each of the compression chambers, an impeller in the impeller chamber, a supply of

- liquid adapted to be caused to flow into one of the compression chambers to compress the fluid therein and to flow from the other compression chamber to draw fluid thereinto, cut offs individual to the compression chamber and operating in opposition to each other, said cut offs controlling the communications between the impeller chamber and the respective compression chambers, liquid by-pass passages leading from each of the compression chambers, a valve for controlling the by-pass passages, there being a liquid passage leading from each of the compression chambers, means whereby the pressure upon the liquid in the last said passages will actuate the said valve to change the course of flow of the liquid from one compression chamber to the other, means for automatically controlling the last said passages, and means whereby the change in the course of flow of the liquid will actuate the said cut offs. 33. A compressor embodying two compression chambers, each having a fluid inlet and an outlet for compressed fluid, an impeller chamber having communication with each of the compression chambers, an impeller in the impeller chamber, a supply of liquid adapted to be caused to flow into one of the compression chambers to compress the fluid therein and to flow from the other compression chamber to draw fluid thereinto, cut offs individual to the compression chambers and operating in opposition to each other, said cut offs controlling the communications between the impeller chamber and the respective compression chambers, liquid by-pass passages leading from each of the compression chambers, a valve for controlling the by-pass passages, there being a liquid passage leading from each of the compression chambers, a piston like element connected with the valve for actuating it, the liquid in the last recited passages adapted to impact said element for actuating it to shift the valve to change the course of flow of the liquid, means operating automatically to control the flow of the liquid through the last recited passages, and means operating automatically to actuate the said cut offs. 34. A compressor embodying two compression chambers each having a fluid inlet and an outlet for compressed fluid, an impeller chamber having communication with each of the compression chambers, an impeller in the impeller chamber, a supply of liquid adapted to be caused to flow into one of the compression chambers to compress the fluid therein and to flow from the other compression chambers to draw fluid thereinto, cut offs individual to the compression chambers and operating in opposition to each other, said cut offs controlling the communications between the impeller chamber and the respective compression chambers, liquid by-pass passages leading from each of the compression chambers, a valve for controlling the by-pass passages, there being and the respective compression chambers, liquid by-pass passages leading from each of the compression chambers, a valve for controlling the by-pass passages, there being a liquid passage leading from each of the compression chambers, means whereby the pressure upon the liquid in the last said passages will actuate the said valve to change the course of flow of the liquid from one compression chamber to the other, means for automatically controlling the last said passages, and means whereby the change in the course of flow of the liquid will actuate the said cut offs, the last recited means embodying formations adapted to be impacted by the liquid for actuating the said cut offs. 35. A compressor embodying two compression chambers each having a fluid inlet and an outlet for compressed fluid, an impeller chamber having communication with each of the compression chambers, an impeller in the impeller chamber, a supply of liquid adapted to be caused to flow into one of the compression chambers to compress the fluid therein and to flow from the other compression chamber to draw fluid thereinto, cut offs individual to the compression chambers and operating in opposition to each other, said cut offs controlling the communications between the impeller chamber and the respective compression chambers, liquid by-pass passages leading from each of the compression chambers, a valve for controlling the by-pass passages, there being a liquid passage leading from each of the compression chambers, a piston like element connected with the valve for actuating it, the liquid in the last recited passages adapted to impact said element for actuating it to shift the valve to change the course of flow of the liquid, means operating automatically to control the flow of the liquid through the last recited passages, and means operating automatically to actuate the said cut offs. 36. A compressor embodying two compression chambers each having a fluid inlet and an outlet for compressed fluid, an impeller chamber having communication with each of the compression chambers, an impeller in the impeller chamber, a supply of liquid adapted to be caused to flow into one of the compression chambers to compress the fluid therein and to flow from the other compression chamber to draw fluid thereinto, cut offs individual to the compression chambers and operating in opposition to each other, said cut offs controlling the communications between the impeller chamber and the respective compression chambers, liquid by-pass passages leading from each of the compression chambers, a valve for controlling the by-pass passages, there being

a liquid passage leading from each of the compression chambers, a piston like element connected with the valve for actuating it, the liquid in the last recited passages adapted to impact the said element for actuating it to shift the valve to change the course of flow of the liquid, and means responsive

in its operation to the pressure in the last recited passages for controlling the flow of the liquid through the latter.

10

In testimony whereof I have signed my name to this specification, on this 12th day of June, A. D. 1923.

MARTEN BALCKER.
